UNITED STATES PATENT OFFICE.

ERNEST O. ESTWING, OF ROCKFORD, ILLINOIS, ASSIGNOR TO ESTWING MANUFACTURING COMPANY, INC., OF ROCKFORD, ILLINOIS, A CORPORATION OF ILLINOIS.

AX SHEATH.

Application filed August 12, 1925. Serial No. 49,745.

This invention relates to an improved sheath for an ax or hatchet.

The principal object is to provide a simple, practical and serviceable ax sheath especially adapted for use when camping, touring, hiking and scouting, and for general sporting use wherever it is a convenience to be able, safely and securely, to carry a small ax on the person after the manner 10 of a side arm, or to pack the sheathed ax without danger of injury to other packed articles.

My invention is fully described in the following detailed description which refers to 15 the accompanying drawing illustrating my invention, wherein;

Fig. 1, is a perspective view of my improved ax sheath illustrating the manner of using the same for carrying a small ax or 20 hatchet in a sling or a belt about the waist;

Fig. 2 is a view looking up at the bottom side of the case with the ax handle appearing in section;

Fig. 3 is a vertical cross-section through 25 the case at the flap with the ax head appearing in section between the side walls of the case and also with the suspensory belt or strap appearing in section between the inside wall of the case and the flap.

30 In the three views, the same reference numerals are applied to corresponding parts.

The sheath comprises a case 4 arranged to receive the head 5 of an ax or hatchet with the handle 6 in depending relation to the 35 head, hanging down the side after the manner of a side-arm, when the case is suspended on a sling or belt 7 on the person of the user. It is contemplated that the sheath can be worn at the waist and that no extra belt 40 will be required, but that the trouser belt may be used with the sheath placed between two of the loops on the trousers and having the belt passing through the loop 8 provided on the case 4 in a manner which will appear 45 more clearly hereinafter.

The case comprises an inner and outer sheathing wall 9 and 10, respectively, of leather or other similar and equally suitable material. These walls may be formed in one 50 piece, but are herein illustrated as separate pieces riveted together along their front edges, as indicated at 11, with a strip 12 of leather or the like interposed between the pieces. The pieces are also stitched together, 55 as indicated at 13, across the front edge of

the case and part way across the bottom up to the rivet 14. At this point, the bottom is provided with an opening 15 through which the ax handle is passed in placing the ax in the sheath. The pieces 9 and 10 are riveted together, as shown at 16, on the other side of the opening 15 opposite the rivet 14. This construction, it will be observed, leaves the entire top side of the case open for the reception of the ax head 5. The sharp edge 60 of the head is encased in the closed front end of the case 4 where the strip 12 serves both as a means of protecting the stitching 13 from abrasion by the sharp edge of the ax, and also prevents dulling of the ax by 65 contact with the rivets. Furthermore, this strip affords reinforcement generally and is a stiffening member giving body to the case. The blunt end of the ax lies at the open rear end of the case as shown.

A flap or tongue 17, is riveted at 18 to the piece 9 and extends upwardly across the inner face of the case 4 and through a slit 19 in the piece 9 to extend across the open top of the case over the ax head therein and 80 down the outer face of the case for fastening. A snap fastener button 20 is provided on the flap 17 which cooperates with a stud 21 riveted in the piece 10. The flap, it will be noted, occurs in line with the opening 15 and thus 85 embraces the ax head in line with the ax handle thereby affording the best possible means for holding the ax in the case both against displacement from the case, and against movement therein. This feature is 90 important in that it gives the wearer freedom of movement and the suspended ax does not constitute a noticeable encumbrance. It will also be observed that the flap provides a loop 8, above referred to, on the inner 95 face of the case through which the belt or strap 7 can be passed, the loop occurring between the fastening 18 and the slit 19 in the piece 9. This arrangement provides for the safe carrying of the case on the trouser belt 100 with or without the ax therein and, even though the flap should be unbuttoned, there is little danger of loss of the case so long as the belt 7 is holding the same, since the flap 17 must first pass through the slit 19 before the case is free. The fastener button 20 obstructs the passage of the flap through the slit and thus prevents accidental displacement and loss of the case. Although all of

the previous references have been made with 110

a view to the carrying of the ax in the sheath on the person of the user, it must be understood that the sheath is equally as well adapted for sheathing an ax or hatchet for storage or packing and will, in such an instance, prevent damage to other packed articles or damage to the sharpened edge of the ax itself. The sheath also serves as a protection against rusting.

10 It is contemplated to use the ax as a hammer with the sheath on it, the sheath serving as a guard for the sharp end of the ax and also to protect the same from dulling.

I claim:

15 1. In an ax sheath, a case to receive the ax head, said case being open across the top but closed across the bottom with the exception of a single opening to pass the ax handle through whereby the head of the ax

20 is received in the case as in a pocket with the handle depending from the case, and means for suspending the case as on a belt or the like and for retaining the ax head in the case, said means comprising a strap fixed

25 on the outside of said case on one side thereof so as to provide a loop between it and the wall of the case to receive the suspensory belt or the like, and said strap being extended across the open top of the case to the

30 other side thereof to close the case on the ax.

2. In an ax sheath, a case to receive the ax head, said case being closed at the front at the sharp edge of the ax and open at the back at the blunt edge of the ax, and being

35 closed on the bottom to suspend the ax, there being a small opening provided in the bottom to pass the ax handle through, but being open across the top to admit the ax head, a fastener flap arranged to be passed over the

40 open top to close the case on the ax and passing down the outer face of the case for fastening, a quickly detachable and attachable fastening for said flap, and a loop provided on the inner face of the case to receive a

45 suspensory belt or sling, said loop being formed by an integral extension of said flap

passing through a slit in the inner wall of said case and down the inner face a certain distance, and permanently fastened to the case.

3. In an ax sheath, a case to receive the ax head, said case being open across the top and having an opening in the bottom thereof for the ax handle, and a fastener flap secured at one end to the one side of said case and passing up through an opening provided in the wall of the case and across the open top to the other side of the case for closing the case on the ax, said flap forming a loop between the secured end thereof and the opening in the wall of the case to receive a suspensory belt or the like.

4. In an ax sheath, a case to receive the ax head, said case being open across the top and having an opening in the bottom thereof for the ax handle, and a fastener flap occurring intermediate the front and rear ends of the case opposite the ax handle opening, secured at one end to the one side of said case and passing up through an opening provided in the wall of the case and across the open top to the other side of the case for closing the case on the ax, said flap forming a loop between the secured end thereof and the opening in the wall of the case to receive a suspensory belt or the like.

5. In an ax sheath, a case to receive the ax head, said case being open across the top and having an opening in the bottom thereof to receive the ax handle, and a flap secured at one end to the one side of said case and passing up through a slit provided in the wall of the case and across the open top to the other side of the case for closing the same on the ax head, said flap forming a loop between the secured end thereof and the slit in the wall of the case to receive a suspensory belt or the like, and having a fastener at its free end providing a projection too large to pass through the aforesaid slit.

ERNEST O. ESTWING.
